ATTORNEY

UNITED STATES PATENT OFFICE.

WILLIAM W. HAYDEN, OF NEWARK, NEW JERSEY.

DESIGN FOR A MATCH-BOX.

SPECIFICATION forming part of Design No. 21,637, dated June 21, 1892.

Application filed May 13, 1892. Serial No. 432,930. Term of patent 3½ years.

To all whom it may concern:

Be it known that I, WILLIAM W. HAYDEN, a citizen of the United States, and a resident of Newark, in the county of Essex and State of New Jersey, have invented and produced a new and original Design for Match-Boxes, of which the following is a specification.

Reference is to be had to the accompanying drawing, forming a part of this specification, 10 in which the figure illustrates my newly-designed match-box or receptacle for small articles.

A represents the body of the box, and B the cover. At the center of the body appears the 15 main relief ornament C, lyre-like in general form, diagonally arranged, and showing the two members a b. From the member a extend several leaf-like ornaments c of scroll order, terminating in small spirals or volutes 20 c', while the lower part of the member b is obliterated by foliation b', so that the whole

presents to the eye the appearance of a flaming Eolian harp or lyre. At the upper and lower corners of the body appear the parallel and slightly-curved strips or ribs d and d', 25 and at or about the center of the bottom and one side of the body appears hatched work or chasing e and e', and between appears a scroll border f, reaching around the corner of the body. Adjacent to the chasing e and lapping 30 upon the parallel ribs d is formed another scroll g as a base to the central ornament. The top or cover shows a foliated ornament h, in relief, with spiral terminals h', as clearly illustrated in the drawing. 35

I claim—

The design for a match-box, substantially as described, and shown in the drawing.

WILLIAM W. HAYDEN.
